ATTORNEY.

Patented Oct. 7, 1924.

UNITED STATES PATENT OFFICE.

CLARENCE H. TWETTEN, OF ROUND LAKE, MINNESOTA.

PERAMBULATOR.

Application filed April 23, 1921. Serial No. 465,104.

To all whom it may concern:

Be it known that I, CLARENCE H. TWETTEN, citizen of the United States, residing at Round Lake, in the county of Nobles and State of Minnesota, have invented certain new and useful Improvements in Perambulators, of which the following is a specification.

This invention relates to new and useful improvements in convertible perambulators and the primary object of the invention is to provide a device of this nature including a removable body which may be used as a coop or den and cradle combined.

Another important object of the invention is to provide a device of this nature, the body of which includes a collapsible structure whereby it may be folded into a compact bundle for transportation.

A further object of the invention is to provide a wheeled chassis having means cooperating with means on the body for preventing movement of the latter with respect to the chassis.

A still further object of the invention is to provide a body which may be either used as a coop or cradle, the rockers being connected to the body in the manner whereby they are maintained stable when in an operative position and are retained in a position so as not to interfere with the rolling of the coop when such movement is desired.

Another object of the invention is to provide a device of the above nature which is strong, durable, inexpensive to manufacture and is highly efficient in practice.

Other objects and advantages of the invention will become apparent during the course of the following description.

In the accompanying drawings forming a part of the application and wherein like numerals are employed to designate like parts throughout the several views,

Figure 1 is a side elevation of the invention.

Figure 2 is a bottom plan of the body.

Figure 3 is an end elevation of the same.

Figure 4 is a longitudinal section of the same showing the rockers folded into an inoperative position.

Figure 5 is a transverse section through the same illustrating the rockers in an operative position.

Figure 6 is a sectional detail of the invention.

Figure 7 is a fragmentary view of a corner of the body.

Figure 8 is a section thereof.

Figure 9 is a fragmentary elevation of the body.

Figure 10 is a detail view showing the manner of mounting the body upon the chassis.

Figure 11 is a fragmentary perspective view of a portion of the chassis illustrating the means for retaining the body thereon.

Referring now to the drawings wherein for the purpose of illustration is shown the preferred embodiment of my invention, the numeral 12 designates a wheeled chassis which may be of either the rigid or collapsible type, and is provided with the ordinary perambulator handle bars 13. A pair of outwardly bowed springs 14 are secured to each end of the chassis and extend a slight distance above the wheels thereof. As best seen in Figure 11, a transverse supporting bar 15 is secured to the upper ends of each pair of springs and the ends 16 of the bars are turned upwardly and provided with thumb screws 17 for a purpose which will hereinafter appear.

The body of the perambulator is indicated in its entirety by the numeral 18 and consists of a bottom 19 having foldable sides and ends hingedly connected thereto by means of hinges 20. These sides and ends forming the walls of the body fold inwardly one upon the other, it being noted best in Figure 5 that the hinges of opposite sides are of different height so that one side may be folded upon the other. The hinges of the two ends are of the same height in the present instance, but it will of course be appreciated that they may be made of varying sizes to suit the dimensions of the body, that is to say that in case the body is not long enough to permit the two ends to lie in the same plane when folded, the hinges may be constructed so as to permit overlapping of the two ends when they are folded inwardly upon the bottom.

Each hinge consists of a pair of sections 21 and 22 as best seen and in Figure 6 and the section 21 is preferably L-shaped so that the horizontal arm thereof may be secured to the bottom of the body and inwardly of the border thereof to permit the lower edge of the wall of the body engaging the upper surface of the bottom when the walls are arranged upright. The walls are provided

with vertical grooves 23 in which are secured the other sections 22 of the hinges, and it will be apparent that when the walls are arranged upright, sections of the hinges lie in their respective grooves 23. Suitable fasteners or clips 24 are secured to certain walls of the body to retain them in upright position. The walls as well as the bottom of the body are preferably padded the padding on the bottom being removable.

Opposite ends of the body are equipped with handles 25 for conveying the body from place to place, and a looped scrape 26 is connected to one end wall for the purpose of providing a convenient means by which the body be rolled.

The same end of the body is provided with a pair of sockets 27 for the reception of depending legs or standards 28 of a one-man top 29. It will of course be obvious that this top may be provided with the usual storm curtain which may be fastened to the sides of the body when occasion demands.

The bottom 19 of the body at each corner thereof is provided with a caster or roller 30 so that the body of the coop or den may be rolled from one part of the house to the other whereby the infant placed therein may be under constant watch of its mother. As best seen in Figure 9, a transversely extending rocker 31 is pivoted adjacent each end of the body to the bottom thereof by means of hinges 32 which will be particularly noted are slightly spaced inwardly of the casters 30 for a purpose which will presently appear. A break-joint link 33 is connected to the bottom of the body for securely retaining the rocker in an operative position when desired.

This link 33 is of a construction that it will become locked when the rocker is opened into an operative position, and the joint of the link may be "broken" to permit the rocker to swing inwardly of the body and into close proximity to the bottom of the body. In order to retain the rocker in an inoperative position, a spring clip 34 is secured to the bottom of the body adjacent each rocker and is adapted to engage the lower edge thereof when it is swung into an inoperative position. It is of course apparent that the rockers are of such height that they will extend below the casters 30 when opened into an operative position so that the body may be readily converted into a cradle.

As stated before, a space is provided between the rocker and the casters at each end of the body so that when it is placed upon the chassis, the bars 15 thereof will be received between the rockers and the casters to prevent accidental longitudinal movement of the body relative to the chassis. The ends 65 16 of the supporting bars 15 will engage

opposite sides of the body, and the thumb screws 17 may be readily tightened to grip the body and securely retain it upon the chassis.

From the foregoing description, it will be apparent that the body may be conveniently removed from the chassis and converted into either a cradle or a coop which may be wheeled around the house from place to place. It will also be obvious that when it is desired to carry the perambulator on trips, the chassis is constructed of the collapsible type to be collapsed as may be the body so that the whole device will only occupy the minimum amount of space. The walls of the body are purposely constructed rather high to prevent the infant from climbing over the sides thereof and will therefore serve as an efficient pen for the child to maintain him under the care of his mother and will also provide an amusement for the child in rock back and forth.

The foregoing description and accompanying drawings have reference to what might be considered to be the approved or preferred form of my invention. I desire it to be understood that I may make such changes in the construction, combination and arrangement of parts, materials, dimensions, etc., as may prove expedient and fall within the scope of the appended claims.

Having thus described my invention what I claim as new and desire to secure by Letters Patent is:

1. In a perambulator, the combination with a wheeled chassis having springs rising therefrom, transverse supporting bars secured to the springs, the ends of the bars being turned upwardly and provided with clamping means, and a body resting upon said supporting bars and having its sides engageable with said clamping means.

2. In a perambulator, the combination with a wheeled chassis, transverse supporting bars carried thereby, of a removable body resting upon said bars and said body being provided with rollers and rockers spaced apart and adapted to be arranged upon opposite sides of the supporting bars for preventing accidental shifting of the body.

3. In a perambulator, the combination with a wheeled chassis having springs rising therefrom, transverse supporting bars secured to the springs, the ends of the bars being turned upwardly, thumb screws extended through said upturned ends of said bars, and a body resting upon said supporting bars and having its sides engageable with said thumb screws.

In testimony whereof I affix my signature in presence of two witnesses.

CLARENCE H. TWETTEN.
